UNITED STATES PATENT OFFICE

SAMUEL T. ECHOLS, OF ST. LOUIS, MISSOURI

ICE SHAVER

Application filed June 29, 1928. Serial No. 289,219.

This invention relates to apparatus for shaving ice, one of the objects being to provide a compact, simple and efficient mechanism which can be set up readily in a small space, 5 such as the top of an ice box where it can be reached conveniently.

Another object is to provide a motor actuated mechanism which will shave the ice quickly, there being adjustable blades for enclosing 10 the ice and reducing it to the desired degree of fineness.

Another object is to provide means for forcibly expelling the finely comminuted ice from the apparatus.

With the foregoing and other objects in view which will appear as the description proceeds the invention resides in the combination and arrangement of parts and in the details of construction hereinafter described 20 and claimed it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a view partly in elevation and partly in section of the complete apparatus.

Figure 2 is a section on line 2-2, Figure 1.

Figure 3 is a section on line 3-3, Figure 1.

Referring to the figures by characters of reference 1 designates a base the top of which is hollowed out to form a drip pan which, 35 as shown, can be formed with a drain cock 2. This base has a boss 3 provided with an opening 4 therethrough and another boss 5 is formed on the base. This last named boss constitutes a support for the base 6 of an electric motor 7 which is held to the base 1 by bolts 8 or any other suitable fastening devices.

Seated on the boss 3 is the base 9 of an arcuate tubular housing 10, there being a delivery tube 11 integral with and extending 45 downwardly from this base 9 and opening, at its upper ends, into the enlarged end portion 12 of the body 10. This enlarged end portion constitutes the housing of the shaving and expelling elements. The shaving element includes a disk 13 provided with slots 14 in

opposed portions thereof and extending through each of the slots is a cutting blade 15 having slots 16 for the reception of clamping screws 17 extending into the disk. The blades are disposed at acute angles relative to the faces of the disk and can be adjusted in the direction of their lengths so as to vary the fineness of the comminuted ice. Disk 13 has a boss 18 secured to one end of the shaft 19 of the motor and this disk is mounted to fit snugly within the arcuate body 10 close to the housing 12 where it will rotate freely.

Secured to the shaft 19 within housing 12 is an expelling element in the form of a fan wheel 20 spaced from the disk 13 and working across the inner side of an opening 21 in the wall of housing 12 through which shaft 19 extends. The upper and lower walls of this opening are inclined downwardly and inwardly as shown whereby moisture will drain into the housing and not outwardly through the opening.

An ear 22 is extended from the body 10 and pivotally connected to it is an arm 23 carrying a follower 24. This follower has a head 25 adapted to swing downwardly into the body 10 for the purpose of forcing the contents of the body longitudinally thereof and against the disk 13. The position of the follower in the body has been indicated by broken lines. A handle 26 is extended from the follower and a stop screw 27 can be carried thereby for engagement with the end of the body to limit the downward movement of the head 25. This screw is adjustable as will be obvious. A stop lug 28 is also extended from the arm 23 and is adapted to engage the housing 12 when the follower 24 is in extreme open position, thereby to support the follower as shown by full lines in Figure 1.

In practice the ice to be shaved is placed in the body 10 and the follower 24 is then swung downwardly so that the head will press against the ice and force it against the disk 13. Motor 7 will cause the disk to rotate at a high speed and the blades 15 will shave through the ice, causing the shavings to pass through the slots 14 in the disk and thence to the housing 12 from which they will gravitate through the outlet tube 11. serves to prevent any of the ice from escaping through the opening 21 and also acts as a means for ejecting the shavings downwardly through the tube 11. Any moisture accumulating on the outer surfaces of the structure either by condensation or otherwise will drain into the hollow base 1 and can be removed therefrom through the drain cock 2.

As before explained, this device, which is very simple and compact, can be attached readily to a suitable support, such as the top of an ice box, etc. It will act to quickly and efficiently shave the ice applied thereto and the construction is such as to reduce to 15 the minimum all danger of moisture dripping from the apparatus on to surrounding structures.

What is claimed is:

1. A device of the class described including a base constituting a drip pan, an arcuate tubular body detachably mounted at one end on the base for receiving ice to be shaved, that portion of the body nearest the base constituting a housing, an outlet tube extending from the bottom of said housing through the base, a shaving element mounted for rotation within the body adjacent to the housing, an expelling element mounted for rotation within the housing above the tube, 20 and a motor on the base for driving said shaving and expelling element.

2. A device of the class described including a base, an arcuate body detachably mounted at one end on the base, said body being tubular, that portion of the body connected to the base constituting a housing, a motor, a shaft extending from the motor into the housing, there being an enlarged aperture in the housing through which the 35 shaft extends, the walls of the aperture being inclined to drain into the housing, an expelling element mounted on the shaft and extending across the aperture for preventing escape of shaved ice through the aperture 40 and directing the same downwardly, a shaving element mounted for rotation between the arcuate body and its housing portion, and an outlet tube extending downwardly from said housing portion for receiving shavings 45 from the shaving element and the expelling device.

3. A device of the class described including a base constituting a drip pan, an arcuate tubular body detachably mounted at one end 50 on said base, said end of the body constituting a housing, an outlet tube depending from and integral with the housing and extending through the base, a slotted disk mounted for rotation in the body close to the housing portion thereof, shaving blades adjustably mounted within the slotted portions of the disk, an expelling fan within the housing but spaced from the disk to provide an un- 55 obstructed passage from the blade to the

outlet, and a motor mounted on the base for driving the disk and fan.

4. Apparatus of the class described including a body having a tubular inlet and an outlet, a shaving element mounted between the inlet and the outlet, a follower movable lengthwise of the tubular inlet for forcing material against the shaving element, and an expelling element between the outlet and the shaving element, said element having all portions thereof spaced from the shaving element to provide at all times an unobstructed passage from the shaving element to the outlet.

5. A device of the class described including a body having an arcuate tubular inlet and an outlet, a shaft mounted for rotation in the body, a shaving element rotatable with the shaft between the inlet and the outlet, a follower within the tubular inlet and movable lengthwise thereof for forcing material against the shaving element, and an expelling element rotatable with the shaft between the shaving element and the outlet, said element including blades radiating from the shaft and having all portions thereof spaced from the shaving element to provide an unobstructed passage from said element to the outlet.

In testimony that I claim the foregoing as my own, I have hereto affixed my signature.

SAMUEL T. ECHOLS.
